INVENTOR:
James Dockett, Jr.
By George Woodworth,
ATTORNEY

UNITED STATES PATENT OFFICE

JAMES DOCKETT, JR., OF ROXBURY, MASSACHUSETTS

GARMENT HANGER

Application filed April 17, 1930. Serial No. 444,992.

My invention relates to garment hangers and the object thereof is to provide a coat hanger or a combined coat and trousers hanger with a removable attachment for supporting a hat, or other articles of apparel, and also other garment hangers.

With the foregoing object in view my invention comprises a garment hanger such as a coat hanger or a combined coat and trousers hanger having a web connecting the upper arms thereof, such web being provided with means whereby a resilient hook may be attached to the hanger at right angles to the plane thereof for receiving a hat, and readily detached therefrom and secured thereto in a position substantially in the plane of said hanger.

An illustrative embodiment of my invention is shown in the drawings which accompany and form a part of this specification in which

Figure 1 is a front elevation of a garment hanger embodying my invention;

Fig. 2 is a side view thereof;

Fig. 3 is a fragmentary front elevation showing the removable rack in inoperative position;

Fig. 4 is a section on an enlarged scale taken on the line 4-4 of Fig. 1; and

Fig. 5 is a fragmentary plan view partly in section on an enlarged scale.

In the particular drawings selected for more fully disclosing my invention the arms 10, 10 and the cross arm 11 formed integral with the suspending hook 12 constitute a well-known form of combined coat and trousers hanger. Attached to and preferably formed integral with the upper portion of the arms 10 is a web 13 provided with two pairs of oppositely-disposed sockets 14, 14 and 15, 15 which sockets are formed in the present instance by punching out portions of the web at right angles to the plane thereof and boring the same, the holes in the vertically disposed sockets 15, 15 preferably being circular and those of the horizontally disposed sockets 14 preferably being rectangular.

A hook 16 of resilient material comprising two reversely bent arms each terminating re-

spectively in the ends substantially at right angles to an arm and preferably rectangular in section, is constructed and arranged to be secured in position to said flange by slightly compressing the same and then inserting the ends 17 in their co-operating sockets, whereupon the hook will be held in position by the elasticity thereof.

As shown in Figs. 1 and 2, the hook is secured to the sockets 14, 14 substantially at right angles to the plane of the web, and as illustrated in Fig. 3, it is attached to the sockets 15, 15 and lies substantially in the plane of web for convenience of shipment or packing.

Preferably the lower arm of the hook 16 is grooved or corrugated as shown at 18 for receiving other garment supporters. Inasmuch as the weight of garments suspended by hooks supported by said lower arm would tend to tilt the entire structure forwardly, said lower arm preferably is inclined upwardly when the plane of the hanger is vertical so that when the hook is weighted by garments suspended therefrom the lower arm will not pass below the horizontal.

Having thus described an illustrative embodiment of my invention without however having limited the same thereto, what I claim and desire to secure by Letters Patent is:

1. A garment hanger comprising in combination a pair of angularly related arms, a web connecting said arms, said web being provided with a pair of oppositely-disposed sockets and a hook of resilient material detachably secured to said web, said hook having an upper and lower arm each terminating in an end substantially at right angles to the arm of which it forms a part and each being shaped to fit into one of said sockets whereby said hook is held by the elasticity thereof to said web substantially at right angles to the plane thereof.

2. A garment hanger comprising in combination a pair of angularly related arms, a web connecting said arms, said web being provided with a pair of oppositely-disposed sockets and a hook of resilient material detachably secured to said web, said hook having an upper and lower arm, said lower arm

being grooved transversely and each said arm terminating in an end substantially at right angles to the arm of which it forms a part and each being shaped to fit into one of 5 said sockets whereby said hook is held by the elasticity thereof to said web substantially at right angles to the plane thereof.

3. A garment hanger comprising in combination a pair of angularly related arms, a 10 web connecting said arms, said web being provided with a pair of oppositely-disposed rectangular sockets, and a hook having an upper and lower arm each terminating in an end substantially at right angles to the arm 15 of which it forms a part, said ends being rectangular in section and arranged to be received by said rectangular sockets whereby said hook is held by the elasticity thereof to said web substantially at right angles of the 20 plane thereof, said web being provided also with a pair of oppositely-disposed circular sockets arranged at right angles to said rectangular sockets, whereby said ends may be inserted in said circular sockets and said 25 hook held to said web substantially in the plane thereof.

In testimony whereof, I have hereunto subscribed my name this 14th day of April, 1930.

30 JAMES DOCKETT, JR.
